United States Patent Office.

SEBASTIAN LEONARD, JR., OF FAIRFIELD COUNTY, OHIO.

Letters Patent No. 71,767, dated December 3, 1867.

IMPROVEMENT IN PORTABLE FENCE.

The Schedule referred to in these Letters Patent and making part of the same.

TO ALL WHOM IT MAY CONCERN:

Be it known that I, SEBASTIAN LEONARD, Jr., of the county of Fairfield, and State of Ohio, have invented a new and useful Improvement in Portable Fences; and I do hereby declare that the following is a full, clear, and exact description thereof, reference being had to the accompanying drawings, in which—

Figure 1 is a perspective view of a section of fence constructed in accordance with my invention, and

Figure 2 is a cross-section through the centres of the fence-posts.

The object of my invention is to construct a fence which can be readily taken down and moved from place to place, and which, when put up, will be as strong and durable as any other now in use.

To enable others to make and use the same, I will now proceed to describe it by reference to the accompanying drawings.

A B are the fence-posts or uprights, to which the bars H are secured in any suitable manner. The post A is provided with two projections at its lower end, a and a', one of which rests against a corresponding projection b, on the post B, while the other affords a bearing for the head of the key C. D is a brace, slotted at its upper end to embrace the posts A and B, and has a mortise at its lower end to receive the key C', which likewise passes through a similar mortise in the cross ground-sill E into the ground, the head of said key bearing against the brace D and holding it in place. At the other end of the cross-sill E is a mortise, into which is inserted the ends of the posts A and B and the key C. The key being driven firmly into the ground and bearing against the projection a' on the post A, renders it impossible to take out the posts without first removing the said keys. e e are bolts passing through the keys C and C', to hold them in place.

What I claim as my invention, and desire to secure by Letters Patent, is—

The combination of the posts A B, the keys C and C', brace D, and cross ground-sill E, all constructed and arranged substantially as and for the purpose described.

SEBASTIAN LEONARD, JR.
